UNITED STATES PATENT OFFICE.

JUNIOR OWENS, OF WASHINGTON, DISTRICT OF COLUMBIA, ASSIGNOR TO AMERICAN BOTTLEDERS OF CARBONATED BEVERAGES, OF WASHINGTON, DISTRICT OF COLUMBIA.

DESIGN FOR A BADGE OR SIMILAR ARTICLE OF MANUFACTURE.

Application filed September 23, 1924. Serial No. 10,887. Term of patent 14 years.

To all whom it may concern:

Be it known that I, JUNIOR OWENS, a citizen of the United States, residing at Washington, in the District of Columbia, have invented a new, original, and ornamental Design for a Badge or Similar Article of Manufacture, as shown in the accompanying drawing.

I claim:

The ornamental design for a badge or similar article of manufacture, as shown.

JUNIOR OWENS.
